UNITED STATES PATENT OFFICE.

IRA ALLEN, OF DANSVILLE, NEW YORK.

AIRSHIP.

1,074,031.

Specification of Letters Patent. Patented Sept. 23, 1913.

Application filed November 18, 1912. Serial No. 732,122.

To all whom it may concern:

Be it known that I, IRA ALLEN, a citizen of the United States, residing at Dansville, in the county of Livingston and State of New York, have invented certain new and useful Improvements in Airships, of which the following is a specification, reference being had therein to the accompanying drawing.

10 This invention relates to flying machines of the dirigible type, and the principal object of the invention is to provide a flying machine of this type in which the propelling and controlling means are mounted upon and within the gas bag.

Another object of the invention is to provide an improved manner for mounting the forward and rear propellers so that they may be turned horizontally in order to assist in guiding the airship.

Another object of the invention is to provide an improved means for driving the forward and side propellers so that the rotation of the propellers may be controlled.

25 Another object of the invention is to provide an improved type of pendulum which is carried by the gas bag and which steadies the machine when in flight.

This invention is illustrated in the accompanying drawings, wherein:

Figure 1 is a top plan view of the machine with the central portion of the gas bag broken away. Fig. 2 is a transverse section along the line 2—2 in Fig. 1. Fig. 3 is a transverse section along the line 3—3 in Fig. 1. Fig. 4 is a side elevation of the flying machine with the central portion broken away to show the arrangement of the driving and controlling means. Fig. 5 is a fragmentary bottom plan view of one end of the gas bag. Fig. 6 is an enlarged fragmentary sectional view taken along the line 6—6 in Fig. 5.

Referring to the accompanying drawings, 45 it will be seen that this invention comprises a car 10 which is supported from the gas bag 11 by means of the rods 12. These rods 12 are secured to the sides and ends of the gas bag and to the bottom of the car so that the car will be securely held in place.

The gas bag comprises the outer casing 13 which is substantially elliptical in cross section and in longitudinal section, and is divided by the partitions 14 and 15 into the 55 central chamber 16 and the end chambers. Each of the end chambers is divided longi-

tudinally to form the central chamber 17 and the side chambers 18. A large gas bag 19 is mounted in each of the central chambers 17 and smaller gas bags 20 are mounted in the side chambers 18. When these bags 19 and 20 are inflated they provide the supporting means for holding the flying machine in the air. Each of these gas bags is provided with a valve 21 so that they 60 may be independently inflated, and, therefore, if one of the gas bags leaks the remaining bags will not need to be emptied in order to repair the leak. This also permits the remaining gas bags to support the machine 65 if the leak occurs while a flight is being made.

A shaft extends transversely through the central chamber 16 and comprises the two sections 22 and 23. These sections each extend through the central bearing 24 of a yoke 25 and carry a beveled gear 26 at its outer end which gear meshes with a beveled gear 27 rigidly mounted upon the axle 28 rotatably mounted in the arms of the yoke 70 25. A propeller blade 29 is mounted upon the forward end of the axle 28 to assist in driving the airship. A wheel 30 is provided at the inner ends of each of the bearings 24 so that the yoke may be turned thus 75 directing the air current created by the propellers 29 and assisting in keeping the airship upon an even keel. A motor 31 is mounted in the central chamber and is provided with a pulley wheel 32 upon its driving shaft. This pulley wheel 32 is connected with a pulley wheel 33 rigidly mounted upon the shaft section 23 by means of the belt 34. It will thus be seen that when the engine is started the section 23 of the transverse shaft will be rotated and as will be 80 hereinafter brought out, the remaining propellers are driven from this section 23.

A longitudinally extending shaft 35 has its ends mounted in the partitions 14 and 100 15 and carries beveled gears 36 and 37 near its center, these beveled gears meshing with beveled gears 38 and 39 rigidly mounted upon the inner ends of the sections 22 and 23 of the transversely extending shaft. 105 Beveled gears 40 and 41 are mounted upon each end of the shaft 35, the beveled gears 40 limiting the longitudinal movement of the shaft 35. A lever 42 is connected with the shaft 35 and is adapted to be rocked to 110 move the shaft 35 longitudinally thus selectively bringing either the beveled gear 36,

or the beveled gear 37 into engagement with the beveled gears 38 and 39. It will thus be seen that by adjusting the shaft 35 longitudinally the direction in which the propeller blades 29 rotate may be regulated.

A vertical shaft 43 is mounted in each end of the central chamber 16 and is provided at its lower end with a beveled gear 44 with which one of the beveled gears 40 or 41 meshes. In accordance with the direction in which the shaft 35 is moved the shaft 43 will be rotated, the gear 41 causing it to rotate in an opposite direction to the gear 40 and thus the direction in which the forward 15 and rear propellers rotate may be regulated. A vertical shaft 45 is mounted in a bracket 46 and is provided at its upper end with a pulley wheel 47 which is connected with a pulley wheel 48 by means of a belt 49. When the shaft 43 is rotated the belt 49 will cause the shaft 45 to rotate, and this shaft 45 will rotate the shaft 50 through the medium of the beveled gears 51 and 52. The shaft 50 passes through a slot 53 formed in 20 a yoke 54 and carries at its outer end a propeller blade 55.

A shaft 56 is rotatably mounted in a set of brackets 57 and is provided with a wheel 58 so that the shaft may be rotated. A cable 59 has its ends wound upon the shaft 56 in opposite directions and has its central portion passing around a pulley wheel 60 rigidly mounted upon the upper end of a vertical shaft 61. This shaft 61 passes 35 through a standard 62 carried by the yoke 54 and has its lower end provided with a gear wheel 63 which meshes with a rack 64. This rack 64 is provided with a lip 65 which travels in a groove formed in the yoke 54 above the slot 53. Therefore, it will be readily seen that when the shaft 56 is turned, it will cause the shaft 61 to rotate and thus move the rack 64 and swing the shaft 50. The forward and rear propellers 40 are driven and operated in a similar manner and, therefore, it will be seen that the description of one of these propellers will serve for both. It will also be seen that these propellers may be independently adjusted as to their horizontal swing but that they will be driven together, that is to say, when the shaft 35 is moved longitudinally the rotation of both of the propeller blades 55 will be reversed.

55 A shaft 66 is mounted in bearings 67 and carries a wheel 68 so that the shaft may be rotated. A cable 69 is wound upon the shaft 66 and has its lower end connected with a toggle bracket 70. A weight 71 for 60 establishing lateral equilibrium is at the lower end of the toggle bracket and swings laterally with the airship as the airship tilts thus bringing the airship back to the proper position. By winding or unwinding the cable 69 the length of the toggle bracket may

be adjusted and thus the swing of the pendulum regulated.

In operating this airship the engine is started and this causes the shaft section 23 to rotate. The longitudinally extending 70 shaft 35 will then be moved to bring either the gear 36 or the gear 37 into engagement with the gear 38 and thus the shaft 35 will be caused to rotate to operate the forward and rear propellers. When the shaft 35 is 75 adjusted either the gear 36 or 37 comes into engagement with the gear 39 and this will cause the shaft section 22 to rotate thus rotating the side propeller upon the opposite side of the airship from the motor. When 80 it is desired to turn the ship, the wheels 58 may be rotated thus swinging the forward and rear propellers and this will assist the ship in turning. The forward and rear propellers may be turned at any angle desired, 85 after being independently operated. If it is desired to reverse the rotation of the propeller blades, the shaft 35 is moved longitudinally and as the shaft is in the position shown in Fig. 1 this adjustment will bring 90 the gear 36 into engagement with the gears 38 and 39 instead of the gear 37, and bring the forward gear wheels 40 and 41 into engagement with the beveled gears 44. When the shaft 35 has been thus moved it will 95 cause the side and end propeller blades to be turned in an opposite direction from that in which they were traveling before and thus cause the ship to move in an opposite direction. The operator for the car sits in 100 the central chamber 16 and the passengers or freight are carried in the car 10. By this arrangement the passengers or freight are carried beneath the supporting bag, whereas the operator is in a chamber in the 105 central portion of the bag and is, therefore, not liable to be interfered with by the passengers or freight.

It should also be noted that the operating mechanism for the car does not take up a 110 lot of room in the car 10 and that it is so arranged that the operator may readily reach all of the parts of the controlling mechanism.

Having thus described the invention, what 115 is claimed as new, is:—

1. A flying machine comprising a supporting bag, a car suspended from said supporting bag, said supporting bag being provided with a chamber intermediate its 120 length, a yoke at each end of said bag, a vertical bearing at each end of said bag, a vertical shaft rotatably mounted in each of said bearings, a propeller shaft having one end pivotally mounted in said bearing and having its outer end passing through a slot 125 formed in said yoke, gears connecting said vertical and propeller shafts, means for rotating said vertical shafts to transmit power to said propeller shafts, propeller blades 130

5 mounted upon said propeller shafts, a bearing carried by each of said yokes, a vertical shaft mounted in each of said last mentioned bearings, a rack bar slidably connected with said yoke and provided with an opening through which said propeller shaft passes, a gear wheel carried by said last mentioned vertical shaft and meshing with said rack bar to move said rack bar and
10 swing said propeller shaft when said last mentioned propeller shaft is rotated, means for rotating said last mentioned vertical shafts, and means in the chamber of said gas bag for controlling the rotation of said
15 propeller shafts and for controlling the rotation of said last mentioned vertical shafts.

2. A flying machine comprising a gas bag provided with a chamber intermediate its length, a car suspended from said gas bag,
20 a yoke at each end of said gas bag, a vertical shaft carried by said yoke, a rack bar

slidably connected with said yoke and provided with an opening intermediate its length, a propeller shaft pivotally connected with the end of said gas bag and passing 25 through the opening of said rack bar and through a slot formed in said yoke, a vertical shaft carried by said gas bag for rotating said propeller shaft, means operated from within said chamber for rotating said 30 last mentioned vertical shaft, and means operated within said chamber for rotating said first mentioned vertical shaft to swing said propeller shaft.

In testimony whereof I hereunto affix my 35 signature in presence of two witnesses.
